(57) **CLAIM**

The ornamental design for a pair of advertising panels with triangular marker for shopping cart corral, as shown and described.

DESCRIPTION

FIG. 1 is a perspective view of the shopping cart corral having triangular markers affixed above advertising panels;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a perspective view of the shopping cart corral having triangular markers affixed above advertising panels;

FIG. 8 is a left side view thereof;

FIG. 9 is a right side view thereof;

FIG. 10 is a front view thereof;

FIG. 11 is a rear view thereof; and,

FIG. 12 is a top view thereof.

The broken line showings of the shopping cart corral in the figures are for the purpose of illustrating an environment only and form no part of the claimed design.

1 Claim, 10 Drawing Sheets
